UNITED STATES PATENT OFFICE.

JOHN DOHERTY, OF LOCKPORT, NEW YORK.

VALVE-GEAR FOR PUMPS.

SPECIFICATION forming part of Letters Patent No. 606,480, dated June 28, 1898.

Application filed December 29, 1897. Serial No. 664,278. (No model.)

To all whom it may concern:

Be it known that I, JOHN DOHERTY, of Lockport, in the county of Niagara and State of New York, have invented a new and Improved 5 Valve-Gear for Pumps, of which the following is a full, clear, and exact description.

This invention relates to an improvement in valve-gears for pumps, and is especially adapted for use with single pumps; and it 10 consists of certain novel features, which will be hereinafter described and claimed.

Reference is to be had to the accompanying drawings, forming a part of this specification, in which similar characters of reference indicate corresponding parts in all the views.

Figure 1 is a side elevation, partially in section, of a pump with my valve-gear attached thereto. Fig. 2 is a longitudinal sectional elevation of the steam-cylinder of a pump and 20 my valve-gear thereon shown in a different position from that of Fig. 1. Fig. 3 is a sectional end elevation between the valve-gear and the water-cylinder, and Fig. 4 is a detail view showing a modified construction for the 25 pivoted dog.

In the drawings my valve-gear is shown as applied to a single pump, in which A represents the steam-cylinder; a, the steam-piston; A', the valve-chest; A², the water-cylinder, 30 and B the valve. These parts may be of any ordinary or desired construction, as the particular constructions shown are not essential in my invention. The steam and water pistons are connected to the usual pump-rod C. 35 This pump-rod is provided with a cross-head or block H, to the sides of which are pivoted blocks H'. The blocks H' are embraced by the slotted ends D² of a pivoted lever D. The lower end of the lever D is forked to make a 40 yoke, each member of which is slotted to embrace the blocks H', pivoted upon each side of the cross-head H. This method of construction is a preferred one for connecting the lever D to the pump-rod C, but is not essential, as any desired form of connection 45 may be used. The lever D is pivoted at e to the connecting portion A³ of the frame, extending between the steam and water cylinders. The upper end of the lever D is forked, 50 forming two arms D', each of which is pro-

vided with a set-screw d, the use of which will be hereinafter described.

A dog or lever E is pivoted to the frame A³, preferably upon the same pivot as that of the lever D, although this is not strictly essential. This dog has its outer end formed with 55 sloping edges or diamond-shaped, the edges E' thereof acting as cam-surfaces. The dog E is also provided with a lateral slot E², adapted to receive a pin b', which is carried by the 60 yoke b. This yoke is connected to the valve-stem either by a rigid connection, as shown in the drawings, or by a pivoted connection, as may be desired. The lever D and dog E thus form a compound lever formed in two 65 sections which are pivoted to each other. By means of the arms D' and the set-screws d the amount of slack between these two sections may be adjusted at will.

Upon guides A⁴, extending upwardly from 70 the frame, is mounted a cylinder F, and within this cylinder is a plunger or piston F', to the lower end of which is pivoted a roller F² by a pin f. The lower end of the plunger F' is formed as a yoke F⁴, which embraces the 75 roller F² and the upper end of the dog E. To the upper end of the plunger F' is fixed a packing ring or plate F³, which is of leather or other suitable material which will form a tight joint for the plunger and prevent leakage of steam. The upper end of the cylinder F is connected by pipes G with the steam-chest of the pump. This connecting-pipe is provided with a throttle-valve J, by which the steam may be throttled and its admission 80 to the cylinder F regulated. A by-pass G' is also provided and a check-valve h opening toward the steam-chest to guard against throttling of the steam as the same is driven out of the cylinder F by the plunger rising. 85

As shown in detail in Fig. 4, the dog E may be provided with two plates I, which are secured by a clamping-bolt I² to one side of the dog E. These plates are provided with slots I', adapted to embrace the clamping-bolt. 90 One end of these plates extends over the slot E². By means of these plates the length of the slot may be reduced and the amount of slack or lost motion between the dog E and the valve-stem may be regulated. The plates 100

I, in fact, may be adjusted so as to entirely do away with this lost motion. By this means the valve may be regulated so as to cut off the admission of steam before the piston has completed its stroke.

The operation of my device is as follows: With the parts in the position shown in Fig. 2, steam is being admitted to the left of the piston, which will force the piston to the right. As it moves in this direction it will swing the lever D, and this will raise the dog E. The cam-surfaces E' of the dog engaging the roller F² will raise the plunger F' until it is resting upon the point of the dog. This will be the position of the dog and plunger shown in Fig. 1, although the lever D will be in a different position from the one shown therein. Any further movement of the piston to the right will swing the dog to the left a sufficient distance, so that the steam-pressure upon the plunger F' will force the same downward, and by engagement of the roller F² with one of the cam-surfaces E' will throw the dog E to the left. The previous movement of the dog has not moved the valve by reason of the extent of the slot E² in the dog. Further movement of the dog will, however, throw the valve toward the left, so as to admit steam to the opposite side of the piston. This latter movement will be a quick one and will insure a full opening of the valve. The steam being admitted to the opposite side of the piston will then force it in the opposite direction. The same operation of the parts will occur until the parts reach the position shown in Fig. 1. A further movement of the piston to the left will result in the dog E being forced to the right by the pressure of the roller F² thereon. It will thus be seen that the movement of the valve is not caused directly by the movement of the pump piston and rods. These, however, indirectly cause the movement of the valve by moving the dog E into position where it will be thrown by the plunger F'. The actual movement of the valve, it will be seen, is caused directly by steam-pressure. In consequence the movement of the valve is a positive one independent of the speed of motion of the pump, and is one quickly accomplished.

This form of valve-gear will thus enable a pump to be run at as slow a speed as desired without any probability of the pump stopping, and in cases where such operation is desired the pump may be stopped for any length of time and will promptly resume operations as soon as the pressure against which the pump is operating is sufficiently reduced.

Having thus described my invention, I claim as new and desire to secure by Letters Patent—

1. A pump valve-gear, comprising a pivoted dog having its outer edge faces inclined toward each other and forming cam-surfaces, a roller mounted to slide toward and from the pivot of said dog and engaging said cam-sur-

faces, a pivoted lever having vibratory connections to the pump-piston and having arms adapted to engage opposite sides of the dog, to vibrate it, but being wider than the dog so as to have lost motion between the two, and connections from said dog to the steam-valve, substantially as described.

2. A pump valve-gear, comprising a pivoted dog or lever having its outer end pointed or diamond-shaped, and a laterally-extending slot therein, a valve-operating rod having a pin extending into said slot, a roller mounted to slide toward and from the pivot of said dog and bearing upon its inclined edges, a pivoted lever having vibrating connection with the pump piston-rod, and arms upon said lever adapted to embrace the dog, to vibrate it, substantially as described.

3. A pump valve-gear, comprising a pivoted dog or lever having its outer end pointed or diamond-shaped and a laterally-extending slot therein, a valve-operating rod having a pin extending into said slot, a cylinder and plunger mounted in line with the pivot of the dog, connections from the cylinder to the steam-supply for the pump, a plunger having a roller engaging the inclined surfaces of the dog, a pivoted lever having vibrating connection with the pump piston-rod, and arms upon said lever adapted to embrace the dog, to vibrate it, substantially as described.

4. A pump valve-gear, comprising a pivoted dog or lever having its outer end pointed or diamond-shaped and forming inclined cam-surfaces and also having a laterally-extending slot therein, a valve-operating rod having a pin extending into said slot, a cylinder or plunger mounted in line with the pivot of the dog, connections from said cylinder to the steam-supply for the pump, a throttling-valve in said steam connection, a by-pass having a check-valve opening toward the steam-supply, a roller mounted upon the plunger and engaging the cam-surfaces of the dog, and a pivoted lever having vibrating connection with the pump piston-rod and arms adapted to embrace the dog, to vibrate it, substantially as described.

5. A pump valve-gear, comprising a pivoted dog or lever having its outer end pointed or diamond-shaped and forming inclined cam-surfaces, connections therefrom to the steam-valve, a yielding plunger having a roller bearing upon the cam-surfaces of the dog and toward its pivot, a pivoted lever having vibratory connection with the pump-rod and having arms embracing the dog, and set-screws extending through said arms whereby the slack or lost motion between the arms and the dog may be regulated, substantially as described.

6. A pump valve-gear, comprising a pivoted dog or lever having its outer end pointed or diamond-shaped and forming inclined cam-surfaces, said dog having a lateral slot, adjustable plates by which the extent of said

slot may be regulated, a valve-stem connection to said slot comprising a pin entering said slot, a yielding plunger having a roller bearing upon the cam-surfaces of the dog and toward its pivot, a pivoted lever having vibratory connection with the pump-rod and having arms embracing the dog, and set-screws extending through said arms, whereby the

slack or lost motion between the arms and the dog may be regulated, substantially as described.

JOHN DOHERTY.
